assignors to Arthur Salm Inc., Chicago, Ill., a corporation of Illinois

Application November 7, 1956, Serial No. 43,692

Term of patent 14 years

(Cl. D74—1)

Fig. 1 is a perspective view of a desk set showing our new design;

Fig. 2 is a perspective view of the letter opener forming a part of the desk set of Fig. 1, the opposite side thereof being similar in appearance;

Fig. 3 is a perspective view of the scissors forming a part of the desk set of Fig. 1; and

Fig. 4 is an end view of the holder forming a part of the desk set of Fig. 1, as it appears with the scissors and letter opener removed therefrom.

We claim:

The ornamental design for a desk set, substantially as shown and described.
